CRANK GRINDING MACHINE

Herbert A. Silven, Worcester, Mass., assignor to
Norton Company, Worcester, Mass., a corpora-
tion of Massachusetts

Application September 11, 1944, Serial No. 553,573

10 Claims. (Cl. 51—72)

This invention relates to grinding machines, and more particularly to a double head crankpin grinding machine.

One object of the invention is to provide a simple and thoroughly practical, readily controllable crankpin grinding machine. Another object of the invention is to provide a crankpin grinding machine with a single lever control which serves to control the various movements of the grinding machine. Another object of the invention is to provide a crankpin grinding machine with a single lever control which serves to interlock the controls for the table traverse, the forward and rearward feeding movement of the grinding wheel, and the positioning of the steadyrest shoes. Another object of the invention is to provide a crankpin grinding machine with a single lever control having a remote control such as an electrically controlled change speed mechanism whereby either the rate of movement of the grinding wheel or the movement of the work table may be readily changed, that is either slowed down or speeded up by means of a manually operable limit switch on the main control lever. Another object of the invention is to provide a solenoid actuated change speed valve in the hydraulic system which is readily controlled by a limit switch mounted on the main control lever.

A further object of the invention is to provide a crankpin grinding machine with a hydraulically operated table traverse mechanism, a hydraulic wheel feeding mechanism, and a hydraulic steadyrest actuating mechanism having independent valves for controlling each of said mechanisms, all of which are actuated by a single control lever. Another object of the invention is to connect one of said valves so that when the machine parts are in an idle position, a balanced pressure relief valve will be actuated to drop the operating pressure in the hydraulic system to zero. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

In the accompanying drawings, in which is shown one of various possible embodiments of the mechanical features of this invention,

Fig. 1 is a diagrammatic illustration of the hydraulic system and electric wiring for controlling the movements of the various machine parts;

5 Fig. 2 is a fragmentary front elevation of a portion of the front of the machine, on an enlarged scale, showing the main control lever and associated parts;

Fig. 3 is a fragmentary end elevation, partly in section, of the parts shown in Fig. 2;

Fig. 4 is a horizontal sectional view, taken approximately on the line 4—4 of Fig. 3, showing the guard for restricting the movement of the main control lever;

Fig. 5 is a fragmentary detail view, showing the connection between the main control lever and the table control valve;

Fig. 6 is a fragmentary detail view, showing the main control lever together with connections between the control lever and the wheel slide control valve, the table control valve, and the auxiliary valve for controlling the hydraulic steadyrest;

20 Fig. 7 is a vertical sectional view, on an enlarged scale, of the balanced-pressure type relief valve;

Fig. 8 is a vertical sectional view, on an enlarged scale, through the wheel slide and table control valves;

Fig. 9 is a sectional view through the auxiliary control valve which controls the steadyrest and also serves as a venting valve for the balanced-pressure relief valve;

30 Fig. 10 is a fragmentary plan view showing the connection between the pivot stud for the main control lever and the shaft for actuating the auxiliary control valve; and

Fig. 11 illustrates a modification of the solenoid actuated valve in which the valve is normally closed.

40 A crankpin grinding machine has been illustrated in the drawings comprising a base 10 which supports a transversely movable wheel slide 11 carrying a rotatable grinding wheel 12. The wheel slide 11 is arranged to slide transversely on the usual V-way and flat way, not shown.

45 A longitudinally movable work supporting table 15 is arranged to slide longitudinally relative to the base 10 on the usual V-way 16 and flat way (not shown). The table 15 serves as a support for a pair of work heads which are preferably of a double head type such as, for example, that shown in my prior U. S. Patent No. 2,151,666 dated March 21, 1939.

50 The wheel slide 11 may be moved transversely to feed the grinding wheel 12 toward or from the work piece manually by means of a nut and screw mechanism comprising a rotatable feed

screw 20 which meshes with a half nut 21 depending from the underside of the wheel slide 11. The feed screw may be operatively connected 10 with a hand wheel (not shown) which is rotatably mounted on the front of the machine base in a manner substantially the same as that shown in my prior U. S. patent above referred to.

In order that the grinding wheel 12 may be moved rapidly toward and from the work piece to be ground, it is desirable to provide a fluid pressure mechanism which supplements the nut and screw feed and serves rapidly to move the grinding wheel toward and from the work. As illustrated in the drawings, a piston rod 22 is operatively connected with the rear end of the feed screw 20. The piston rod 22 is connected to a piston 23 which is slidably mounted within a cylinder 24. The cylinder 24 is fixedly mounted relative to the base 10. When fluid under pressure is admitted through a pipe 25 into a cylinder chamber 26, the piston 23 will be moved toward the left (Fig. 1). During this movement, fluid within a chamber 27 at the left-hand end of the cylinder 24 will be exhausted through a pipe 28. The control of fluid under pressure to the feed mechanism above described will be explained in detail hereinafter.

The work table 15 is preferably arranged so that it may be traversed longitudinally by means of a hydraulically operated mechanism comprising a cylinder 30 which is fixed relative to the base 10. A slidably mounted piston 31 is provided within the cylinder 30 having a double end piston rod 32 which extends through the opposite end caps on the cylinder 30. The opposite ends of the piston rod 32 are connected by brackets 33 and 34 respectively depending from the under side of the table 15. When fluid under pressure is admitted through a pipe 35 into a cylinder chamber 36, the piston 31 will be caused to move toward the right (Fig. 1) to transmit a corresponding movement to the table 15. During the movement of the piston 31 toward the right, fluid within a cylinder chamber 37 will be exhausted through a pipe 38. Similarly, when fluid under pressure is passed through the pipe 38 into the cylinder chamber 37, the piston 31 and the table 15 will be moved in a direction toward the left (Fig. 1). The mechanism for controlling the admission to and exhaust of fluid from the cylinder 30 will be described hereinafter.

Hydraulic control

When grinding the crankpins on a crankshaft, it is necessary that the wheel be moved through a considerable distance in order that the table may be traversed to position successive pins in operative relation with the grinding wheel. It is highly desirable to interlock the table traverse mechanism, the wheel feeding mechanism, and the steadyrest actuating mechanism so that the table cannot be traversed when the wheel and the steadyrest are moving toward or from the work, and so that the wheel cannot be fed toward the work or the steadyrest moved into an operative position during the table traversing movement to position successive crankpins in operative relation with the grinding wheel. In the preferred construction, a pair of control valves (Figs. 1 and 8) are provided, one of which serves to control the admission to and exhaust of fluid from the table traverse cylinder 30 so that either a fast or a slow traverse may be obtained in either direction, and the other of which serves to control

the admission of fluid to and the exhaust of fluid from the wheel feed cylinder 24.

As illustrated in the drawings, a control valve 40 is provided for controlling the admission of fluid to the feed cylinder 24. The control valve 40 is preferably a piston type control valve comprising a valve stem 41 having formed integrally therewith valve pistons 42, 43, 44 and 45.

A fluid reservoir 46 is provided either in the base of the machine or is positioned adjacent thereto. A motor driven fluid pressure pump 47 is provided to draw fluid through a pipe 48 from the reservoir 46 and to pass fluid under pressure through a pipe 49 into a valve chamber located between the valve pistons 43 and 44.

A control valve 55 is provided for controlling the longitudinal traversing movement of the work table 15. This valve is preferably a piston type valve comprising a valve stem 56 having formed integrally therewith a plurality of valve pistons 57, 58, 59, 60, 61, 62, 63 and 64. Fluid under pressure from the fluid pump 47 passing through the pipe 49 is also conveyed into a valve chamber located between the valve pistons 60 and 61.

In the position of the valves 40 and 55 as illustrated in Figs. 1 and 8, no motion will be transmitted to either the grinding wheel or the work table, both valves being positioned in a neutral or central position.

An exhaust pipe 65 is provided for controlling the exhaust of fluid from the valve 55 when the table 15 is traversing at a normal traversing speed in one direction. A similar exhaust pipe 66 is provided for controlling the exhaust of fluid from the valve 55 when the table 15 is traversing at normal speed in the opposite direction. In order to obtain a very slow, uniform speed of the table for a truing operation or to slow down the table movement just prior to engagement of the stop dogs, auxiliary exhaust pipes 67 and 68 are provided, each having a control valve 69 and 70, respectively, by means of which the speed of movement in either direction may be readily controlled. The valves 69 and 70 are connected to a common exhaust pipe 71 which leads directly to the reservoir 46.

The exhaust pipes 65 and 66 are similarly connected to a common exhaust pipe 72 which in turn connects with the exhaust pipe 52 so that the exhaust pipe 52 carries the entire exhaust from both the wheel slide control valve 40 and the table traverse control valve 55. The exhaust pipe 52 is provided with a throttle valve 73 by means of which the exhaust of fluid from either the wheel slide control valve 40 or the table control valve 55 may be readily controlled. In order to allow a rapid positioning movement of either the grinding wheel slide 11 or the work table 15, a solenoid-actuated slow-down valve 75 is provided.

This valve comprises a valve stem 76 having formed integrally therewith a pair of valve pistons 77 and 78. The outer end of the valve stem is provided with a spool-shaped member 79 which is connected by means of a pin 80 with a downwardly extending arm 81 of a bell crank lever 82. The bell crank lever 82 is pivotally mounted on a stud 83. The horizontally extending arm 84 of the bell crank lever 82 is connected by a stud 85 with a link 86 which is in turn connected by a stud 87 with an armature 88 of a solenoid 89. In the position of the valve 75 as illustrated in Fig. 1, fluid exhausting through the pipe 52 from either the wheel slide control valve 40 or the table control valve 55 may pass from the pipe 52 through a pipe 90, into a valve chamber 91 located between

the valve pistons 77 and 78 of the control valve 75, and outwardly through a pipe 92 into the reservoir 46. A bushing 74 within the valve 75 serves as a stop, normally to locate the valve pistons 77 and 78 in an open position. When the solenoid 89 is energized, the bell crank lever 82 will move in a counterclockwise direction to shift the valve stem 76 toward the right against the compression of a spring 93 so that the valve piston 77 will close a port at the end of the exhaust pipe 90 after which fluid exhausting through the pipe 52 must pass through the throttle valve 73 to slow down the movement of either the wheel slide or the table, depending upon which of the mechanisms is in an operative position.

As shown in Fig. 1, the solenoid actuated valve 75 is illustrated as a normally open valve in which closing of the valve by actuation of the solenoid 89 serves to cut off unrestricted exhaust of fluid and thereby slow down either the table or the wheel slide movement. In certain grinding operations it may be desirable to provide a normally closed valve which may be opened when desired so that a slow traversing movement of the work table or a slow feeding movement of the grinding wheel slide may be speeded up when desired. As illustrated in Fig. 11, a modified form of the valve 75 is illustrated in which the stop bushing 74 is eliminated and the valve pistons 77 and 78 positioned in an extreme left-hand end position so that no fluid may pass from pipe 90 into pipe 91.

If desired, the valve stem 76 and valve pistons 77 and 78 may be so designed and arranged that when it is desired to shift from a normally open to a normally closed valve, it is merely necessary to remove the bushing 74 from the valve casing 75 and shift the valve stem 76 end for end and then re-assemble into the condition illustrated in Fig. 11. The other parts of the valve and actuating mechanism therefor, as illustrated in Fig. 11, are identical with that shown in Fig. 1, consequently the same reference numerals have been used. In the operation of the valve as illustrated in Fig. 11, during the normal movement of the table 15 or wheel slide 11, fluid exhausting from the valves 55 and 40 respectively passes through the throttle valve 73 so as to produce a slow traversing movement of the table or a slow feeding movement of the grinding wheel 12. When it is desired to speed up the movement of the table or the wheel slide, an electric circuit is closed to energize the solenoid 89 (Fig. 11) which causes the valve stem 76 to move toward the right so that the valve pistons 77 and 78 move into a position so that substantially unrestricted exhaust of fluid may pass from the pipe 90 into the pipe 92 and return to the reservoir 46.

Steadyrest

A steadyrest 100 is provided comprising a pair of steadyrest shoes 101 and 102 which are preferably arranged to be moved to and from an operative position by means of a fluid pressure cylinder 103 which contains a slidably mounted piston 104. The details of the steadyrest are not considered to be a part of the present invention, consequently they have not been illustrated in detail nor will they be described herein. This steadyrest is identical with that shown and described in my copending U. S. application Serial No. 534,241 filed May 5, 1944, to which reference may be had for details of construction not found herein.

A pair of pipes 105 and 106 are connected with

5 opposite ends of the cylinder 103. An auxiliary control valve 107 is provided for controlling the admission to and exhaust of fluid from the steadyrest cylinder 103. The valve 107 is preferably a piston type valve comprising a valve stem 108 having formed integrally therewith a plurality of valve pistons 109, 110, 111 and 112. Fluid under pressure passing from the pressure pump 47 through the pipe 49 may also pass through a pipe 113 into a cylinder chamber 114 located between the valve pistons 110 and 111. In the position of the valve illustrated in Fig. 9, fluid under pressure entering the valve chamber 114 may pass outwardly through the pipe 106 to cause the piston 104 to move toward the left so as to move the steadyrest shoes 101 and 102 into an inoperative position. During movement of the piston 104 toward the left (Fig. 1), fluid within the cylinder chamber at the left-hand end of the cylinder 103 may exhaust through the pipe 105 into a valve chamber 115 and pass outwardly through an exhaust pipe 116 into the reservoir 46.

Single control lever

25 In order that the valves 40, 55 and 107 may be operated jointly in timed relation with each other to interlock the movements of the various parts of the machine, a single manually operable control lever 120 is provided. The lever 120 is pivotally connected to a supporting bracket 121 by means of a stud 122. The bracket 121 is preferably formed as a yoke-shaped member 121 which straddles the lower end of the lever 120 and is pivotally connected thereto by means of a stud 122. The yoke-shaped member 121 is rotatably supported relative to the base 10 by means of a stud 123 so that the control lever 120 may be swung toward or from the base of the machine about the axis of the stud 122 as a pivot or may be swung in a direction parallel to the base 10 by movement of the lever about the axis of the stud 123 as a pivot. The valve stem 41 is provided with a sleeve 124 fixed on the outer end of the stem. A rod 125 having slabbed-off parallel sides is fixedly mounted in projections 126 of the sleeve 124 and extends in a longitudinal direction relative to the base 10. The lever 120 is provided with a yoked member 127 which straddles the rod 125. It will be readily apparent from the foregoing that when the lever 120 is moved toward or from the machine base pivoting about the stud 122, a corresponding movement of the yoked member 127 serves to move the rod 125, the sleeve 124, and the valve stem 41 to change the position of the valve 40 so as to control the admission to and exhaust of fluid from the wheel feed cylinder 24.

30 The lever 120 is arranged to swing in a direction parallel to the base 10 about the stud 123 and the mechanism is so connected that the lever serves to control the position of the valve 55 to control the longitudinal movement of the table 15. The valve stem 56 is provided at its outer end with a grooved, spool-shaped member 128 which is connected by a pin 129 with the long arm 130 of a bell crank lever 131. The bell crank lever 131 is provided with a short arm 134 which is preferably in the form of a pin riding in a bushing 135 in the control lever 120. The pin or short arm 134 fits freely within the bushing 135 so that the lever 120 may be moved toward and from the machine base without changing the position of the bell crank lever 131. When the lever 120 is moved either toward the right or toward the left,

that is, parallel with the machine base, the bell crank lever 131 is rocked about its pivot stud 132 to shift the valve stem 56 so as to change the position of the control valve 55 so as to obtain either a fast or a slow traversing movement of the table 15 either in a direction toward the right or toward the left, as viewed in Fig. 1, depending upon the position of the lever 120.

In order that the auxiliary control valve for controlling the steadyrest may be operated in the desired timed relationship with the wheel slide control valve 40 and the table control valve 55, an inter-connection is provided comprising a rotatable shaft 137 which is journaled in bearings 138 and 139 on the front of the machine base 10 (Fig. 6). An arm is fixedly pinned to the left-hand end of the shaft 137. The arm 140 is provided with a pin 141 which engages a spool-shaped grooved member 136 which is fixedly mounted on the end of the valve stem 108. In order to allow the pivot stud 122 to rock with the control lever as the control lever 120 is moved parallel to the machine base, a sliding connection is provided between the pivot stud 122 and the shaft 137. The shaft 137 is preferably provided with a slabbed-off end portion 142 having parallel side faces which mate within a slot 143 (Fig. 10) formed in the pivot stud or shaft 122.

It will be readily apparent from the foregoing disclosure that the pivot stud 122 may swing in a plane parallel to the front of the machine base relative to the shaft 137 without becoming disconnected therefrom. When the lever 120 is moved toward or from the machine base to transmit movement of the control valve 40 to the valve stem 41 to initiate either a forward or a rearward feeding movement of the grinding wheel 12, a rocking motion will be transmitted through the shaft 137 and the arm 140 to move the valve stem 108 and thus shift the auxiliary control valve 107 so that the steadyrest 100 will be operated in timed relation with the wheel feeding movement. When the wheel is moved toward the work, at the start of the grinding operation, the auxiliary control valve will be moved so as to admit fluid under pressure through the pipe 105 to move the piston 104 into the position illustrated in Fig. 1 so that the work steadyng shoes 101 and 102 are moved into operative supporting engagement with a work piece.

In order that the movement of the control lever 120 may be rapidly positioned in one of several different positions to interlock the movements of the valves 40, 55 and 107 so as to control the traversing movement of the work table 15, the feeding movement of the grinding wheel slide 11, the positioning of the steadyrest shoes 101 and 102, and the venting of the hydraulic system when the machine is idle, it is desirable to provide a suitable guiding member to control the movements of the lever 120. As illustrated in Fig. 4, a guide plate 144 is mounted on the base of the machine 10 and is provided with a cross-shaped slot 145 therein which serves to restrict the movement of the control lever 120 in its movement toward and from the machine or longitudinally relative to the machine base. In the full line position of the lever 120a (Fig. 4), the valves 40 and 55 are in the position illustrated in Fig. 1, in which position the table 15 is stationary and similarly the wheel slide 11 is stationary and in a rearward or inoperative position. When the lever 120 is in position 120a, the auxiliary control valve 107 is in a venting position so that the

fluid pressure within the hydraulic system is substantially zero.

When it is desired to start the machine, the lever 120 is moved from position 120a into position 120b (Fig. 4). The lever 120 may then be shifted toward the left into position 120c or toward the right into position 120d which movements shift the control valve 55 so as to start a traversing movement of the table 15 toward the left or toward the right. If the lever 120 is shifted into position 120e or 120f, the traversing movement of the table is slowed down due to the fact that the valve 55 has been shifted so that fluid exhausting therefrom must pass through the throttle valve 69 or the throttle valve 70. It will be readily apparent that when the control lever 120 is moved through toward the left or toward the right, it cannot be shifted forwardly due to the shape of the guiding plate 144, thus preventing a wheel feeding movement during the traversing of the work table 15 to position the work piece relative to the grinding wheel 12.

When it is desired to cause an infeeding movement of the grinding wheel 12 after the work piece has been positioned relative the grinding wheel, the control lever 120 is shifted into position 120g which movement serves to shift the valve 40 so as to initiate a forward feeding movement of the grinding wheel slide 11 of the grinding wheel 12. It will be readily apparent that when the control lever 120 is in a forward feeding position, namely, in position 120g, the control lever cannot be moved lengthwise relative to the machine to actuate the table traverse control valve. It will thus be seen that the guiding plate 144 serves to interlock the wheel feeding movement and table traversing movement relative to each other.

Pressure relief

In order to conserve power and prevent undue heating of the oil due to "wire drawing" of the oil, when the table 15 and the wheel slide 11 are in inoperative positions, it is desirable that the system be so arranged that the fluid pressure will be automatically reduced substantially to zero by allowing fluid from the pressure pump 47 to pass substantially unrestricted back to the reservoir 46. As shown in Fig. 1 of the drawings, a pressure pipe 146 is connected to the main pressure pipe 49 from the pump 47. The pipe 146 is connected to a check valve 147. The check valve 147 is provided with a movable valve member 148 which is normally urged to a closed position by means of a spring 149. The check valve 147 is connected by a pipe 150 with a chamber 151 of a balanced-pressure relief valve 152. The relief valve 152 is of a balanced-pressure type, comprising a valve member 153 and a seat 154 therefor. A piston 155 is formed integral with the valve member 153. A bleeder hole 156 passes through the piston 155 and serves to allow fluid under pressure to pass therethrough into a valve chamber 157. The valve chamber 157 is connected by means of a passage 158 with the ball check valve 149 which is normally held in a seated or closed position by means of a compression spring 160. An adjusting screw 161 is provided for adjusting the compression of the spring 160 as desired.

In order to reduce the pressure in the fluid system to substantially zero, a venting control is provided for relieving the pressure within the valve chamber 157. The passage 158 is connected with a passage 162. The passage 162 is

in turn connected with a pipe 163 which connects with the auxiliary control valve 107. A pipe 164 connects the balanced-pressure relief valve 152 with the reservoir 46. When the auxiliary control valve stem 108 is moved into the right-hand position (Fig. 9), the venting pipe 163 will connect through a port 165 with a valve chamber 166 formed between the valve pistons 111 and 112 and pass through holes 167 into a central aperture 168 within the valve stem 108 and outwardly through holes 169 into the valve chamber 115 located between the valve pistons 109 and 110 and through the exhaust pipe 116 into the reservoir 46. When the venting pipe 163 is opened to the exhaust, fluid under pressure may pass through the bleeder hole 155, the valve chamber 157, the passage 158, the passage 162 and through the pipe 163 which exhausts directly into the reservoir 46, thus unbalancing the pressures on opposite sides of the piston 155 so that the piston remains open and allows substantially unrestricted passage of fluid under pressure directly through the chamber 151 and the pipe 163 into the reservoir 46, thus reducing the fluid pressure in the entire hydraulic system substantially to zero during the time the machine is idle.

The operation of this improved grinding machine will be readily apparent from the foregoing disclosure. A work piece (not shown) is located in position on the work table 15 while the main control lever 120 is positioned in position 120a (Fig. 5). In order to locate the table in the desired position for a grinding operation, the lever 120 is shifted from position 120a into position 120b, after which it may be moved either toward the left into position 120c to cause the table 15 to move toward the left or into position 120d to cause the table 15 to move toward the right so as to facilitate positioning a work piece in a predetermined position relative to the grinding wheel. After the work piece has been positioned in the desired location, the control lever 120 is shifted into position 120b after which it may be moved forward toward the operator into position 120g to admit fluid under pressure to the wheel slide cylinder 24 so as to initiate a forward feeding movement of the grinding wheel 12. After the work piece has been ground to the desired and predetermined size, the control lever 120 may be again shifted from position 120g into position 120a, which movement serves to shift the valve 40 so as to cause a rearward movement of the grinding wheel 12. When the lever 120 reaches the position 120a, the auxiliary control valve is shifted to its rearmost position so that the venting pipe 163 is opened to allow fluid under pressure to exhaust from the balanced pressure relief valve 152 through the pipe 153 and through the valve 107 into the exhaust pipe 116 and return the same to the reservoir 46. The venting of the valve 152 serves to drop the pressure of fluid within the hydraulic system substantially to zero during the time the machine is idle, thus preventing wire drawing of the oil and excessive heating thereof.

During the positioning movement of the table by movement of the control lever, if it is desired to slow down the rapid traverse of the table from a normal speed to a slow-down speed, the control lever may be shifted from position 120c into position 120e or from position 120d into position 120f. This movement serves to shift the valve 55 so that fluid exhausting therefrom, instead of exhausting through the normal exhaust pipes 65

and 66, will exhaust through pipes 67 and 68 and pass through the throttle valves 69 and 70 which are regulated to produce the desired slow movement of the work table 15.

When it is desired to change the normal traversing speed of either the work table 15 or the wheel slide 11, that is, for either a slow-down or a speed-up movement thereof, the operator actuates a limit switch 170 which is located on the hand control lever 120. Actuation of the switch 170 serves to energize the solenoid 89 and thereby to shift the stem 75 of the valve 75 toward the right. If the valve 75 is a normally open valve, as shown in Fig. 1, energization of the solenoid 89 serves to close the valve and thus to slow down the exhaust of fluid from either the table or the wheel slide cylinder so that it must pass through the throttle valve 73 to produce a slow traversing or feeding movement thereof. If the valve 75 is arranged as a normally closed valve, as illustrated in Fig. 7, movement of the valve stem 76 toward the right upon energization of the solenoid 89 serves to open the valve to allow substantially unrestricted exhaust of fluid from the pipe 90 to pass through pipe 92 into the reservoir 46, thus producing a speed-up movement of either the work table 15 or the wheel slide 11, depending upon which is operative.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawings is to be interpreted as illustrative and not in a limiting sense.

I claim:

1. In a grinding machine having a base, a longitudinally movable work table thereon, a piston and cylinder to traverse said table, a rotatable grinding wheel, a transversely movable grinding wheel slide, a piston and cylinder to feed said slide in either direction, a control valve for said table cylinder, a control valve for said wheel slide cylinder, a manually operable control lever which is operatively connected to actuate both of said valves, a throttle valve to control the exhaust of fluid from both of said valves, means including a valve to by-pass exhaust fluid around said throttle valve, and remote control means on said control lever which is operatively connected to actuate said valve to change the rate of exhaust and thereby change the rate of movement of either the table or the wheel slide.

2. In a grinding machine having a base, a longitudinally movable work table thereon, a piston and cylinder to traverse said table, a rotatable grinding wheel, a transversely movable grinding wheel slide, a piston and cylinder to feed said slide in either direction, a control valve for said table cylinder, a control valve for said wheel slide cylinder, a manually operable control lever which is operatively connected to actuate both of said valves, a throttle valve to control the exhaust of fluid from both of said valves, means including a solenoid actuated valve to by-pass exhaust fluid around said throttle valve, and remote control means including an electric switch on said control lever which is operatively connected to actuate said solenoid valve to change the rate of

exhaust and thereby change the rate of movement of either the table or the wheel slide.

3. In a grinding machine having a base, a longitudinally movable table thereon, a piston and cylinder to traverse said table, a rotatable grinding wheel, a transversely movable grinding wheel slide, a piston and cylinder to feed said slide in either direction, a control valve for said table cylinder, a control valve for said wheel slide cylinder, a manually operable control lever which is operatively connected to actuate both of said valves, a throttle valve to control the exhaust of fluid from both of said valves, means including a normally open solenoid actuated valve to by-pass exhaust fluid around said throttle valve normally to allow substantially unrestricted exhaust of fluid to control the normal speed of the table or wheel slide, and means including an electric switch on said control lever which is operatively connected to actuate said solenoid to close said solenoid actuated valve to slow down the rate of movement of either the table or the wheel slide.

4. In a grinding machine having a base, a longitudinally movable table thereon, a piston and cylinder to traverse said table, a rotatable grinding wheel, a transversely movable grinding wheel slide, a piston and cylinder to feed said slide in either direction, a control valve for said table cylinder, a control valve for said wheel slide cylinder, a manually operable control lever which is operatively connected to actuate both of said valves, a throttle valve in said exhaust pipe to control the exhaust of fluid from both of said valves, a normally closed solenoid actuated valve to by-pass fluid around said throttle valve, and means including an electric switch on said control lever which is operatively connected to actuate said solenoid to open said valve so as to allow substantially unrestricted exhaust of fluid to speed up the rate of movement of either the table or the wheel slide.

5. In a grinding machine having a base, a longitudinally movable work table thereon, a piston and cylinder to traverse said table, a rotatable grinding wheel, a transversely movable grinding wheel slide, a piston and cylinder to feed said slide in either direction, a control valve for said table cylinder, a control valve for said wheel slide cylinder, a manually operable control lever which is operatively connected to actuate both of said valves, said connections being arranged so that when the lever is moved in one direction it serves to actuate the table control valve and when moved in a second direction serves to actuate the wheel slide control valve, a throttle valve to control the exhaust of fluid from both of said valves, means including a solenoid actuated valve to by-pass fluid around said throttle valve, and means including an electric switch on said control lever which is operatively connected to actuate said solenoid so as to change the rate of exhaust and thereby change the rate of movement of either the table or the wheel slide.

6. In a grinding machine having a base, a longitudinally movable work table, a piston and cylinder to traverse said table, a rotatable grinding wheel, a transversely movable grinding wheel slide, a piston and cylinder to feed said slide in either direction, a control valve for said table cylinder, a control valve for said wheel slide cylinder, a manually operable control lever which is operatively connected to actuate both of said valves, a common exhaust pipe to return fluid exhausting from both of said control valves, a sole-

noid valve in said exhaust pipe line normally to allow unrestricted exhaust of fluid from said valves, means including a throttle valve to bypass exhaust fluid around said solenoid valve when said solenoid valve is closed to produce a slow movement of either the table or the wheel slide, and means including a limit switch on said control lever which is operatively connected when closed to actuate and close said solenoid valve after which fluid exhausts through said throttle valve to facilitate slowing down either the movement of the table or the wheel slide.

7. In a grinding machine having a base, a longitudinally movable work table thereon, a piston and cylinder to move said table in either direction, a transversely movable grinding wheel slide, a piston and cylinder to feed said slide in either direction, a control valve to control the direction and speed of movement of said table, a second control valve to control the direction of movement of said wheel slide, a manually operable control lever which is connected to actuate both of said valves, a common exhaust pipe to return fluid exhausting from both of said cylinders through said control valves, a solenoid valve in said exhaust line which is normally open to allow unrestricted exhaust of fluid from either of said valves so that either the table or the wheel slide will move at a relatively fast speed, means including a throttle valve to by-pass fluid around said solenoid valve when said solenoid valve is closed, and means including a limit switch on said control lever which is operatively connected to close said solenoid valve so as to facilitate slowing down the movement of either the table or the wheel slide.

8. In a grinding machine as claimed in claim 1, the combination with the parts and features therein specified, of an auxiliary valve which is operatively connected to control the direction of movement of the steadyrest shoes, operative connections between said auxiliary valve and said control lever whereby said auxiliary valve is actuated in timed relation with said wheel slide control valve.

9. In a grinding machine as claimed in claim 1, the combination with the parts and features therein specified, of a balanced type relief valve in said system normally to maintain a predetermined operating pressure in said system, and an auxiliary valve which is actuated by said control lever when moved to a predetermined position in one direction to vent and open said relief valve automatically to reduce the pressure in said system when both the table and wheel slide are inoperative.

10. In a grinding machine having a base, a longitudinally movable work table, a piston and cylinder to traverse said table, a rotatable grinding wheel, a transversely movable grinding wheel slide, a piston and cylinder to feed said slide in either direction, a control valve for said table cylinder, a control valve for said wheel slide cylinder, a main control lever which is operatively connected to actuate both of said valves, a balanced type relief valve in the system normally to maintain a predetermined operating pressure in said system, and an auxiliary valve which is actuated by said control lever when moved to a predetermined position to vent and open said relief valve automatically to reduce the pressure in said system.

HERBERT A. SILVEN.
